STANLEY CHARLES BRYANT, OF CHICAGO, ILLINOIS, ASSIGNOR TO BRYANT ZINC COMPANY, OF CHICAGO, ILLINOIS, A CORPORATION OF ILLINOIS.

TIME-CONTROLLED HIGHWAY-CROSSING ALARM.

1,296,360.

Specification of Letters Patent.

Patented Mar. 4, 1919.

Application filed July 13, 1916. Serial No. 109,037.

To all whom it may concern:

Be it known that I, STANLEY CHARLES BRYANT, a citizen of the United States, and a resident of the city of Chicago, in the county of Cook and State of Illinois, have invented a new and useful Time-Controlled Highway-Crossing Alarm, of which the following is a specification.

This invention relates to signaling devices or alarms used for protecting highway crossings, and more particularly to such highway crossing alarms which are operated for a certain period of time.

One of the objects of this invention is to devise a novel, simple and reliable highway crossing alarm which will sound or otherwise perform its signaling function for a certain length of time after its operation is initiated.

A further object of the invention is to devise a novel, simple and reliable time controlled circuit controller for use in connection with highway crossing alarms which will perform its circuit controlling function after the lapse of a predetermined time following its initial operation.

Other objects and advantages of the invention will appear hereinafter as the description of the invention progresses, and the novel features of the invention will be pointed out in the appended claims.

In the accompanying drawing, in which is illustrated the preferred physical embodiment of the invention, and in which like reference characters refer to like parts in the several views,

Figure 1 is a side view of a time controlled circuit controller constituting part of the invention; Fig. 2 is a view of the right-hand end of the circuit controller shown in Fig. 1; Fig. 3 is a fragmentary enlarged section taken horizontally through the circuit controller substantially on the line 3—3 in Fig. 1 and looking in the direction of the arrows; and Fig. 4 is a diagrammatic view, in the nature of a wiring diagram, which shows the electrical connections between the parts embodying this invention.

Referring to the accompanying drawing, one form of a time controlled circuit controller forming part of the highway crossing alarm embodying the invention is shown mounted in a casing comprising a base plate 1, a cover or top plate 2, and corner posts 3, the sides and ends of the casing between the corner

posts being preferably filled with glass so as to protect the mechanism from dirt and dampness and also to permit ready inspection of the parts.

Secured to the base plate 1 is a small electric motor M of suitable construction capable of maintaining a constant speed; and the armature shaft 4 of said motor M is connected to a shaft 5 which is journaled in the upright members 6 of an inverted U-shaped bracket B fixed to the base plate 1, and to which is fixed a worm 7. Integral with the side members 6 of the bracket B is a horizontally extending arm 8 having an offset end portion 9; and journaled at its upper end in said arm 8 and at its lower end in a boss 10 integral with the base plate 1 is a vertical shaft 11, to which is fixed a worm wheel 12 meshing with the worm 7 on the shaft 5. A shaft 13 having screw threads 14 cut in its periphery for the greater part of its length is journaled at its upper end in the offset end portion 9 and at its lower end in a boss 15 integral with the base plate 1; and fixed to the shaft 13 at its lower end is a large gear 16 which meshes with a pinion 17 fixed to the shaft 11. Arranged to operate at times with the threads 14 on the shaft 13 is a hook-shaped member 18 (see Fig. 3) which is fastened by a plate 19 and a screw 20 to one end of an arm 21. The other end of the arm 21 is pivotally connected to the upper end of an armature 22 of an electromagnet E, the lower end of said armature 22 being pivotally mounted on a pin 23 supported by lugs 24 integral with the base plate 1.

The armature 22 has an extension 25 which is arranged to engage the base plate 1 and limit the movement of the armature away from the electromagnet E; and the armature 22 is urged to this retracted position (shown in Fig. 1) by a tension spring 26, one end of which is connected to said armature and the other end of which is connected to a rod 27 adjustably mounted in an upright member 28 secured to or integral with the base plate 1. The end portion of the pole piece of the electromagnet E opposite to the end adjacent to the armature 22 is threaded and is fastened by a nut 29 in a hole in a lug 30 integral with the base plate 1, so that said base plate forms part of the magnetic circuit for said electromagnet. In the upright member 28 is adjustably secured

a stop pin 31 which is arranged to limit the downward movement of the arm 21, so that when the electromagnet E is deenergized and its armature 22 retracted by the spring 26, the arm 21 falls by its own weight to the position shown in Fig. 1, in which the hook-shaped member 18 is near the lower end of the shaft 13.

- Arranged above the arm 21 is a circuit controlling arm 32, one end of which is fastened to blocks 33 of insulating material, which blocks are in turn fastened to a supporting member 34 which has integral lugs at its edges pivotally connected by pins to lugs 35 projecting downward from the top plate 2; and the said supporting member 34 has a tail portion 36 extending downward and toward the arm 21 at an angle into position to be engaged by a roller 37 journaled in the upper end of a support 38 adjustably secured to said arm 21. The other end of the circuit controlling arm 32 is provided with a contact piece adapted to make good electrical contact with a contact arm 39 supported by a binding post 40 secured in the top plate 2 but insulated therefrom in any suitable or well known manner. A weight 41 is fastened to the circuit controlling arm 32 and normally holds said arm in its lower position as shown in Fig. 1, in which electrical connection is established between said arm and the contact arm 39; and the arm 32 is connected by a flexible conductor 42 to a binding post 43 also secured in the top plate 2 and insulated therefrom. A third binding post 44 is also secured in the top plate 2 so as to be insulated therefrom; and a wire 45 connects this binding post with one end of the winding of the electromagnet E, a wire 46 also connecting this binding post with one terminal of the motor M. The other end of the winding of the electromagnet E is connected by a wire 47 to the binding post 43; and the other terminal of the motor M is connected by a wire 48 to the binding post 40. The above mentioned wires are shown in part in Figs. 1 and 2 as clearly as possible without obscuring the parts of the mechanism and are clearly shown diagrammatically in Fig. 4.
- Referring to Fig. 4, the time controlled circuit controller above described is illustrated as used in connection with the control of a crossing bell or similar alarm A. As is well understood by those skilled in the railway signaling art, crossing bells are usually set into operation by the closing of certain electrical contacts by the movement of a train past a point at a distance from the crossing, by means of a track instrument, track relay, interlocking relay, or the like; and such electrical contacts which are closed by the approach of a train are illustrated diagrammatically in Fig. 4 by the contact bar 49 and its co-operating contact point 50

shown as an arrow. With the time controlled circuit controller there is used a relay, which by reason of the mode of its control is commonly termed a stick relay, and this stick relay is illustrated in Fig. 4 according to established convention and is designated 51, and its contact fingers or armatures are designated 52 and 53. A suitable source of electric current, as a battery 54, is used for supplying the current to operate the relay 51, the electromagnet E, the motor M and the bell A.

The various wires and electrical connections between the parts shown in Fig. 4 will not be set forth in detail since these electrical connections and the various circuits established will be set forth in detail in the following description of the operation.

Operation: Referring particularly to Fig. 4, when a train approaches the crossing protected by the bell A, it causes the closing of the contact arm 49 with its contact point 50, whereupon a circuit for energizing the stick relay 51 is established as follows: commencing at one terminal of the battery 54, wires 55 and 56, relay 51, wires 57 and 58, contact point 50, contact arm 49, wires 59 and 60, binding post 43, flexible wire 42, circuit controlling arm 32, contact arm 39, binding post 40, and wires 61 and 62 back to the other terminal of the battery 54.

As soon as the armature 52 of the stick relay 51 is raised to its upper position, a stick circuit for said relay is established as follows: commencing at one terminal of the battery 54, wires 55 and 56, relay 51, wires 57 and 63, armature 52 in its upper position, wires 64 and 60, binding post 43, flexible conductor 42, circuit controlling arm 32, contact arm 39, binding post 40, and wires 61 and 62 back to the other terminal of the battery 54.

As soon as the armature or contact finger 53 of the stick relay 51 is raised to its upper position, a circuit for ringing the bell A is established as follows: commencing at one terminal of the battery 54, wires 55 and 65, armature 53 in its upper position, wires 66 and 67, bell A, and wires 68 and 62 back to the other terminal of the battery 54.

Also, when the armature 53 of the stick relay 51 is raised to its upper position, the electromagnet E is energized and the motor M simultaneously supplied with current, the circuit for energizing the electromagnet E being as follows: commencing at one terminal of the battery 54, wires 55 and 65, armature 53 of the relay 51 in its upper position, wires 66 and 69, binding post 44, wire 45, electromagnet E, wire 47, binding post 43, flexible conductor 42, circuit controlling arm 32, contact arm 39, binding post 40, and wires 61 and 62 back to the other terminal of the battery 54.

The circuit for supplying current to the 13

motor M is as follows: commencing at one terminal of the battery 54, wires 55 and 65, armature 53 of the relay 51 in its upper position, wires 66 and 69, binding post 44, wire 5 46, motor M, wire 48, binding post 40, and wires 61 and 62 back to the other terminal of the battery 54.

Referring to Figs. 1, 2 and 3, when the electromagnet E is energized, it attracts its 10 armature 22 against the opposition of the spring 26 and moves the arm 21 and the hook-shaped member 18 to the left as viewed in Figs. 1 and 3 so that the edge of said member is brought into engagement with the 15 threads 14 on the shaft 13, and since the motor M is simultaneously supplied with current, the shaft 13 is driven by the motor M through the intermediate gearing in an obvious manner; and it is apparent that as the 20 shaft 13 revolves, the hook-shaped member 18 and the outer end of the arm 21 are gradually raised at a rate depending on the speed of the motor M, the reduction gearing and the pitch of the threads 14. After the lapse 25 of time for which the mechanism is set, the arm 21 is raised to the point where the roller 37 carried thereby strikes the tail portion 36 of the supporting member 34, whereupon the circuit controlling arm 32 is raised out of 30 electrical contact with the contact arm 39, so as to break the stick circuit for the relay 51 and the circuit for energizing the electromagnet E. As soon as the electromagnet E is deenergized, the spring 26 pulls its armature 22 to the position shown in Fig. 1 so as to move the hook-shaped member 18 out of engagement with the threads 14 on the shaft 13, thereby permitting the arm 21 to immediately assume its normal lower position. 35

40 As soon as the stick circuit for the relay 51 is broken, the armatures or contact fingers of said relay fall to their lower position, the armature 52 opening another break in the stick circuit, and the armature 53 interrupting the circuit for supplying current to the motor M and also the circuit for the bell A. In this way the bell A is sounded for a certain length of time after the initial closing of the contact arm 49 on its contact point 50, 45 and after the elapse of this time, the parts are automatically restored to the normal position ready for the next operation.

It should be noted that the circuit for energizing the electromagnet E includes the 50 circuit controlling arm 32, so that said electromagnet, as well as the stick relay 51, is deenergized by the raising of said circuit controlling arm at the expiration of the time for which the mechanism is set, thereby permitting the arm 21 to immediately move to

its lower position so as to be at the initial point in its travel in case the relay 51 is immediately reenergized as, for instance, by a second following train.

Obviously various changes may be made 55 in the particular construction shown and described without departing from my invention, and I do not wish to be limited to the details of this construction as shown and described. 70

What I claim is:

1. In a time controlled highway crossing alarm, in combination: a crossing alarm; a normally closed circuit controller for governing said alarm; an electric motor; a 75 movable member adapted to open said circuit controller; reduction gearing operated by said motor; electromagnetic means for connecting said movable member with said reduction gearing; and circuits for simultaneously supplying current to said motor and to said electromagnetic means, the circuit for said electromagnetic means including said circuit controller. 80

2. In a time controlled highway crossing 85 alarm, in combination: a crossing alarm; a normally closed circuit controller for governing said alarm; a screw-threaded shaft; an electric motor; gearing connecting said motor and said shaft; a movable member adapted to engage said circuit controller and having a sharp edge adapted to engage the threads of said shaft; an electromagnet for moving said member into engagement with the threads of said shaft; and means for 90 simultaneously supplying current to said electromagnet and to said motor. 95

3. In a time controlled highway crossing alarm, in combination: a crossing alarm; a stick relay for controlling said alarm; a 100 stick circuit for said relay; a normally closed circuit controller included in said stick circuit; a movable member adapted to open said circuit controller; an electric motor; a reduction gearing operated by said motor; 105 electromagnetic means for connecting said movable member to said reduction gearing; and circuits controlled by said relay for simultaneously supplying current to said electromagnetic means and to said motor. 110

4. In a time controlled highway crossing alarm, in combination: a crossing alarm; a stick relay for controlling said alarm; a stick circuit for said relay; electrically operated means for opening said stick circuit 115 after the lapse of a predetermined time; and electrically operated means included in said stick circuit and adapted to control the action of said circuit opening means.

STANLEY CHARLES BRYANT.
